United States Patent Office.

ELIAS INGRAHAM, OF BRISTOL, CONNECTICUT.

Design No. 3,851, dated February 15, 1870.

DESIGN FOR CLOCK-CASE.

The Schedule referred to in these Letters Patent and making part of the same.

To all whom it may concern:

Be it known that I, ELIAS INGRAHAM, of Bristol, county of Hartford, and State of Connecticut, have invented a new and useful Design or Pattern for a Clock or Time-Keeper Case; and to enable others skilled in the art to make the same, I will proceed to describe, referring to the photographic drawings, in which the same letters indicate like parts in each of the figures.

In the accompanying photographic drawings is shown a new and original design or pattern for a clock or time-keeper case.

a is the case proper.

b is a zigzag plain molded edge or side of said case.

c is a plain flat surface or front of the case.

d is a plain molded sash.

e is a time-indicating dial.

All are combined to produce a plain rich design or pattern for a clock or time-keeper case.

What I claim, and desire to secure by Letters Patent, is—

The design or pattern for a clock or time-keeper case, substantially as shown and set forth.

ELIAS INGRAHAM. [L. S.]
